JAMES MCGUIRE AND JOHN M. BONG, OF MILWAUKEE, WISCONSIN.

STEAM-CYLINDER DRAIN-VALVE.

1,319,404.

Specification of Letters Patent. Patented Oct. 21, 1919.

Application filed August 5, 1918. Serial No. 248,410.

To all whom it may concern:

Be it known that we, JAMES MCGUIRE and JOHN M. BONG, both citizens of the United States, and residents of Milwaukee, 5 in the county of Milwaukee and State of Wisconsin, have invented certain new and useful Improvements in Steam-Cylinder Drain-Valves; and we do hereby declare that the following is a full, clear, and exact 10 description thereof.

Our invention relates to new and useful improvements in drain valves for the cylinders of steam engines, more particularly of that type associated with the piston cylinders of locomotives.

Such valves are normally urged to open position, draining the cylinder, when the engine is not running, and are held closed by steam pressure in the cylinder during 20 operation of the engine. Due, however, to the relatively cool cylinder in initially starting the engine, a heavy condensation of steam occurs at that time with a consequent considerable accumulation of water in the 25 cylinder.

It is therefore primarily the object of our invention to provide a steam cylinder drain valve which may be operated to carry off, during operation of the engine, the heavy 30 accumulation of water of condensation which occurs upon starting up such operation.

It is a further object to provide a valve of this character which may also serve to 35 vent the cylinder of a locomotive when the locomotive is "coasting," and thus prevent the occurrence of retarding pressures in the cylinder.

A still further object resides in the provision of a valve of this character which is 40 exceedingly simple and durable in construction and susceptible of ready operation for the novel functions stated.

With these and other objects in view, 45 which will be apparent as the description proceeds, our invention resides in the novel features of construction, combination and arrangement of parts as hereinafter described and defined by the appended claim, it being 50 understood that changes in the precise embodiment might be made by those skilled in the art without departing from the spirit of the invention.

This invention in one practical form in which it may be embodied is illustrated in 55 the accompanying drawing in which:

Figure 1 is a vertical longitudinal sectional view through our improved steam cylinder drain valve.

Fig. 2 is a transverse sectional view there- 60 through on the line 2—2 of Fig. 1.

Referring now more particularly to the accompanying drawings, 5 designates the depending hollow boss of one end of a locomotive piston cylinder, which is adapted to 65 receive the drain valve. Our improved drain valve comprises an upper casing section 6 which has its upper end portion slightly reduced for threaded engagement in the boss 5 and terminating in a valve seat 7. The bottom 8 of the upper casing section is provided with a central bore in which is slidably mounted the stem 9 of a valve head 11 adapted to engage on the seat 7, the valve seat being spaced a sufficient distance 75 from the inner periphery of the cylinder that the valve does not project therewith in opening movement. The lower portion of the upper casing section is provided with an outlet port 12, and the upper surface of the 80 bottom 8 is frustoconical in shape whereby to afford complete drainage of water through said outlet port from the casing. The mouth of a lower cup-shaped casing section 13 is threaded on the bottom of the 85 upper section, and the stem 9 extends into this lower section and carries a piston 14 slidably therein, said stem having its lower end portion reduced to form a consequent shoulder engaged by the piston. The valve 90 is normally urged to raised position in the absence of pressure in the steam cylinder by an expansive coil spring 15 having one end seated in a recess of the piston and its other end seated in an inner countersunk portion 95 of an attaching nipple 16 projecting from the bottom of the lower casing section. Threaded in this nipple is a pipe 17 which extends to one port of a three-way valve 18 having its other port communicating respectively with a pipe 19 leading to a suitable source of compressed air, and with the atmosphere.

In operation, the spring 15 holds the valve open in the absence of operating pressures in the steam cylinder, to thus permit

- free drainage of the cylinder to prevent damage from freezing. This is the general operation of the conventional drain valves. When the operation of the engine is started and a heavy condensation occurs in the cylinder which it is highly desirable to drain off, the valve 18 is operated to admit compressed air through the pipe 17 into the lower casing portion 13, to thus raise the piston and open the valve against any steam pressures which may occur in the cylinder, thus providing a drainage simultaneously with full operation of the engine. It is noted that opening movement of the valve is facilitated by the fact that the area of the piston 14 is considerably greater than the area of the valve head 11. In valve opening movement, the outer peripheral portion of the piston seats against the corresponding portion of the bottom 8 of the upper casing section and thus leakage of the compressed air is prevented, the intermediate portions of the opposed faces of the piston and casing section bottom being cupped to facilitate this engagement. Upon proper drainage of the steam cylinder, pressure is relieved in the casing section 13 by opening the three-way valve 18 to the atmosphere, and the steam cylinder pressures will close the valve 11 against the action of its lifting spring 15. When a locomotive is "coasting," air pressure will be introduced into the casing section 13 to hold the valve 11 open during the period of coasting and thus vent the steam cylinder to prevent the occurrence of retarding pressures therein. An exceedingly simple and durable arrangement has thus been provided whereby the steam cylinder of a locomotive may be, at any time, vented for the purposes set forth, regardless of pressure conditions in the cylinder.
- What is claimed is:
- A valve of the class described comprising- 45
a cup-shaped upper casing section provided with an outlet port and having its upper portion threaded for engagement in the drain outlet of a cylinder, said casing section being cupped in its bottom surface 50
to afford an annular bearing face and having its lower peripheral portion threaded, a cup-shaped lower casing section having its mouth threaded on said lower portion of the upper casing section and provided 55
with an air port in its bottom, a stem slidably passed through the bottom of the upper casing section, and having its lower end portion reduced, a valve head on the upper portion of the stem for closing said 60
upper casing section, a piston disk on the reduced lower portion of the valve stem and slideable in the lower casing section and having an annular bearing face on its top adjacent its periphery engageable against 65
the bottom bearing face of the upper casing section, a projection on the piston disk adapted to extend into the cupped portion of the upper casing section, a nut threaded on the reduced portion of the stem for holding 70
the piston disk, the bottom of the piston disk and the bottom of the lower casing section being provided with opposed recesses and an expansile coil spring disposed between said parts with its ends en- 75
gaged in the recesses.
- In testimony that we claim the foregoing we have hereunto set our hands at Milwaukee, in the county of Milwaukee and State of Wisconsin.
- JAMES McGUIRE.
JOHN M. BONG.
